RACK FOR NURSING BOTTLES

Walter Dorwin Teague, Annandale, N. J., and Gordon M. Peltz, Kew Gardens, and Milton Immermann, Piermont, N. Y., assignors, by mesne assignments, to Continental Can Company, Inc., New York, N. Y., a corporation of New York

Original application July 30, 1948, Serial No. 41,554, now Patent No. 2,604,222, dated July 22, 1952. Divided and this application January 18, 1951, Serial No. 206,604

3 Claims. (Cl. 29—288)

1

This invention relates to improvements in nursing units of the type which comprises a flanged nipple and a disposable container member and is more particularly concerned with a rack for use in assembling the nipple and the container member and thereafter supporting one or more of the filled nursing units in a refrigerator or other storage compartment.

This application is a division of application Serial No. 41,554, filed July 30, 1948, for a Nursing Unit and Method and Apparatus for Assembling the Same, now Patent No. 2,604,222 issued July 22, 1952.

It is a general object of the invention to provide a supporting rack which is adapted to facilitate the assembling and filling of a nursing unit which is characterized by a flexible disposable bottle, a flanged nipple, and ring members for connecting the margins of the bottle with the flange on the nipple in fluid-tight relationship.

It is a more specific object of the invention to provide a stand for use in assembling and supporting nursing units of the type which is characterized by a disposable container of flexible material, a connecting ring and a nursing nipple having a base flange terminating in a reversible clamping skirt for securing the top margins of the container over the connecting ring and in communicating relation with the nipple, which stand comprises a generally rectangular open frame having a flange member projecting upwardly from the top thereof and provided with a peripheral recess in the outer edge in which a connecting ring is adapted to be seated while the marginal portions of the flexible container top are folded thereover and the nursing nipple is secured thereto by the clamping skirt provided on the nursing nipple.

Another object of the invention is to provide in apparatus for assembling a flexible disposable nursing bottle in communicating relationship with a nursing nipple having a depending reversible skirt thereon, a stand having an upwardly extending shoulder formation thereon for supporting an inner attaching ring in position for placing thereover in outwardly folded relation the marginal edges of the bottle whereby to permit the nursing nipple to be secured over the bottle top by moving the reversible skirt into position around the folded portion of the bottle to clamp the same into fluid-type relationship on the attaching ring.

These and other objects of the invention will be apparent from a consideration of the rack which is shown by way of illustration in the accompanying drawings, wherein:

Fig. 1 is a partial side elevation of a rack

2

adapted for use in assembling and thereafter supporting a nursing unit which rack incorporates therein the principle features of the invention;

5 Fig. 2 is an end elevation of the supporting rack;

Fig. 3 is a partial plan view of the supporting rack; and

Figs. 4, 5, 6 and 7 are fragmentary sections 10 illustrating the manner of using the rack for assembling the nursing unit.

Referring to the drawings there is illustrated a support unit or rack which incorporates therein the principles of the invention and which is 15 adapted for use in assembling a nursing unit of the character disclosed in the parent application Serial No. 41,554.

The nursing unit with which the rack is 20 adapted to be used comprises a bottle member 10 which is formed of transparent sheet material into flattened tubular shape and sealed at one end with the other end open for reception of the nursing fluid and for connection with a nursing nipple 12. The open end of the bottle member 10 is formed with a diameter which 25 will permit the top or mouth portions to be folded out and over and down around the outer periphery of an inner rigid attaching or securing sing 11.

30 The attaching ring 11, which is preferably formed of metal or other rigid material 11, which is preferably formed of metal or other rigid material, is of relatively small cross section providing an outer peripheral face 14 which constitutes one of the clamping surfaces for securing the container top and the nipple 12.

The nursing nipple 12, which is formed of rubber-like material, is of the wide base type and is provided with an integral flange or skirt portion 15 which is reversible about a hinge line 16 where it connects with the base of the nipple. The skirt portion 15 is provided with a groove 17 adjacent the upper extremity and on the internal surface when the skirt is in depending position, which groove 17 is of a width corresponding approximately to the depth of the attaching ring 11 and is relatively shallow.

45 The nursing unit may also include an outer clamping ring or band 13 of relatively rigid material which is adapted to be positioned over the flange 15 of the nipple 12 when it is in down-turned bottle top clamping relation.

The supporting rack (Figs. 1 to 3) may 50 comprise a plurality of duplicate units for assembling and supporting any desired number of the nursing devices. For the purposes of illustra-

tion only an end section or unit is shown in the drawings. It will be understood that any number of duplicate units may be incorporated in the rack.

The supporting rack comprises a pair of laterally spaced upright open frame members 33 which are connected at the base by cross pieces 34 and at the top by cross pieces 35. The rack is provided on the top with upstanding flanges 36 which may be formed integral with the top flanges. The flanges 36 extend inwardly and are curved to form an upstanding tube-like section. They are provided at the top edge thereof with a shoulder forming recess 37, which is of a size to receive the small attaching ring member 11 of the nursing unit. The flanges 36 may be formed to provide a complete tube section or their ends may be spaced, as illustrated, to provide open sides. The flanges 36 will be arranged in spaced relation lengthwise of the rack when a plurality of the units are provided on a single rack.

While the nursing unit may be assembled by hand without the use of a tool for expanding and holding the top of the bottle, the assembly is simplified and facilitated by using a tool of the character disclosed in Serial No. 41,554, which includes a band 21 (Figs. 4 and 5) adapted to be inserted within the margins of the bottle top and expanded to grip the internal surfaces thereof. With the bottle or container thus held in mouth expanded relation the body of the container 10 is passed through the tube section formed by the flanges 36 on the supporting rack, the connecting ring 11 having first been positioned in the recess 37. The container is positioned in the rack and the margins are manipulated to bring them into downwardly folded relation as shown in Fig. 5. This may be accomplished by moving the band 21 downwardly until the lower edge of the band 21 is approximately at the upper edge of the ring 11 and then, while holding the body of the bottle 10 against further movement, moving the band 21 further downwardly around the periphery of the flange 36 on the rack until it abuts against the inwardly extending horizontal flange portions 38. This movement strips the bag top from the band 21 and permits removal of the band 21 by expanding the same and moving it upwardly, with the bag top remaining in reverse folded relation on the connecting ring 11.

With the container positioned in this fashion on the flanges 36 the milk or other fluid is placed therein. The nipple 12 is then positioned with the skirt 15 in the upward extending relation over the mouth of the container as indicated in Fig. 6, after which the skirt 15 is reversed or turned downwardly over the folded portions of the bottle or container 10 to clamp the container 10 to the ring 11 as shown in Fig. 7. The unit is then ready to be removed vertically from the rack for use or it may be stored while on the rack and removed for use at a later time.

An outer clamping ring or band 13 may be applied over the skirt 15 of the nipple 12 to further clamp the skirt 15 over the marginal portions of the container 10 as indicated in Fig. 7 before the entire assembled nursing unit is removed from the rack.

While specific details of construction have been referred to in describing the illustrated form of the invention it will be understood that other details may be employed without departing from the spirit of the invention.

We claim:

1. A device for use in assembling a nursing

unit which nursing unit is characterized by a flexible receptacle adapted to be secured to a ring-like connecting member by a nursing nipple having a reversible skirt thereon, said device comprising a generally rectangular hollow supporting frame and a hollow tube-like formation extending upwardly of the top of the frame, said tube-like formation having an outer recess adjacent the upper edge thereof forming a circular shoulder adapted to receive the ring-like connecting member of the nursing unit with the body of the receptacle extending downwardly within said tube-like formation and the marginal portions of the receptacle folded outwardly around the connecting ring in position to receive the skirt of the nipple in clamping relation over said marginal portions.

2. A stand for use in assembling a nursing unit which nursing unit is characterized by a flexible receptacle adapted to be secured to a rigid connecting ring member by a nipple having a reversible skirt thereon, said stand being adapted to support the ring member and the receptacle while the nipple is attached thereto, said stand comprising a generally rectangular supporting frame having upstanding end frame portions and a horizontal connecting top cross frame portion, upwardly extending oppositely disposed curved flange members on the top cross frame portion, said flange members having an inwardly offset shoulder forming portion at the upper edge thereof adapted to accommodate the ring member of the nursing unit, said top cross frame portion being open between said flange members to permit the body of the receptacle to hang downwardly therefrom in the frame and the marginal portions of the receptacle to be folded outwardly and downwardly over said ring member and said flange members whereby the nipple may be positioned on the upper edge of the ring member and the skirt of the nipple reversely folded into clamping relation over said marginal portions.

3. A stand for use in assembling a nursing unit which nursing unit is characterized by a flexible receptacle adapted to be secured to a rigid ring-like connecting member by a nipple having a reversible skirt thereon, said stand comprising a generally rectangular supporting frame, upwardly extending curved flange members of substantial depth on the top of said frame, said flange members having a shouldered portion at the upper edge thereof forming an outwardly facing circular support adapted to receive the ring-like connecting member of the nursing unit, said stand being open between said flange members to permit the body of the receptacle to extend downwardly within said flange members and the marginal portions of the receptacle to be folded outwardly and downwardly over said flange members and said ring-like connecting member in position to receive the skirt of the nipple in clamping relation over said marginal portions.
